DENTAL FLASK

Thomas A. Webber, Hyattsville, Md.

Application December 1, 1950, Serial No. 198,582

6 Claims. (Cl. 18—33)

1

My invention relates to a dental flask.

A primary object of my invention is to provide a dental flask which is smaller than conventional mold boxes or flasks now in use, and more convenient to use for investing a wide variety of work such as partial lower or upper bars, plastic jacket crowns, whole bridges with pressed on teeth, and the like.

A further object of the invention is to provide a hinged dental flask having small flask sections or cups constructed so that a portion or portions of the invested work may project outwardly of the flask, so that it is unnecessary to embed the entire piece of work in the molding material of the cups.

A further object is to provide a dental flask including flask sections or cups which are so constructed that it is much easier to dislodge the molding material from the cups and the invested work from the molding material, than in conventional flasks or mold boxes.

A further object is to provide a hinged dental flask having novel and simplified means for resiliently and firmly holding the flask sections together while the work is invested.

A still further object of the invention is to provide a dental flask of the above-mentioned character which is highly simplified, rugged and durable, and quite inexpensive to manufacture.

Other objects and advantages of the invention will be apparent during the course of the following description.

In the accompanying drawings, forming a part of this application, and in which like numerals are employed to designate like parts throughout the same,

Figure 1 is a perspective view of a hinged dental flask embodying my invention, and showing work invested within the same.

Figure 2 is a transverse vertical section taken on line 2—2 of Figure 1.

Figure 3 is a perspective view of the flask empty and shown partly opened.

Figure 4 is a plan view of the flask in a completely open or extended position.

Figure 5 is a plan view of the flask in the closed position.

Figure 6 is an end elevation of the closed flask, and,

Figure 7 is a side elevation of the same.

In the drawings, where for the purpose of illustration is shown a preferred embodiment of my invention, the numerals 10 and 11 designate elongated bars or arms formed of heavy gauge sheet metal, metal plate stock, or the like. The arms 10

2

and 11 have short converging portions 12 and 13 near their rear ends, and interfitting hinge knuckles 14 and 15 are formed upon the portions 12 and 13 and receive a pintle 16, hingedly connecting the arms 10 and 11 so that they may swing from their closed substantially parallel positions, Figure 7, to their fully opened or extended positions, Figure 4. The arms 10 and 11 may thus swing relative to each other through substantially 10 180 degrees, and the arms are substantially rigid. The arms 10 and 11 are relatively narrow as viewed from the side of the device, Figure 7, and relatively wide and flat transversely, Figure 4. The arm 11 may be slightly longer than the arm 10, as shown.

The arm 11 is provided near and inwardly of its free end and in its opposite longitudinal edges with a pair of opposed arcuate notches 17, for a purpose to be described. The arm 11 is further 20 provided near its free end with a small opening 18 to facilitate hanging up the hinged flask on a nail or the like when it is not in use.

The arm 10 is provided at its forward or free end and transverse center with a hook 19, integral therewith, and the hook 19 is directed laterally outwardly and away from the opposed arm 11. The hook 19 is substantially opposite the notches 17, as shown.

Near and inwardly of the free ends of the arms 30 10 and 11, a pair of opposed channel sections or cups 20 and 21 have their flat bottoms 22 rigidly secured to the inner faces of the arms, by spot welding or the like. The cups 20 and 21 extend transversely of the arms 10 and 11 and slightly 35 beyond the opposite longitudinal edges of the arms, and the opposite ends of the cups are open. The cups 20 and 21 include flat opposed sides or skirts 23, integral with the bottoms 22 and extending transversely of the arms 10 and 11. The sides 23 project laterally inwardly of the inner opposed faces of the arms 10 and 11, and have straight longitudinal edges 24, forming stops. The sides 23 of each cup converge slightly toward the cup bottom 22, so that the molding material 45 is more readily removable from the cups. The edges 24 of the cups are adapted to meet when the arms 10 and 11 are swung to their closed positions, and the edges 24 serve as stops to limit the closing of the arms. The arms 10 and 11 are 50 parallel, as shown, when the edges 24 of the cups 20 and 21 are in contact.

The cups 20 and 21 are provided at their opposite ends and in their bottoms 22 with arcuate recesses or notches 25, extending throughout substantially the entire widths of the cups. The

notches 25 are curved longitudinally of the arms 10 and 11, as shown. The sides 23 are rounded at their corners, as at 26. The inner surfaces of the cups 20 and 21 are smooth, and all of the parts of the device are free from sharp edges, burrs, and the like.

In use, the hinged flask may be swung open to its position shown in Figure 4, and the cups 20 and 21 filled with plaster of Paris or some other suitable molding material, as shown clearly in Figures 1 and 2. The work W to be invested is now embedded in the plaster of Paris mass of one of the cups, while the mass is still soft and one side of the work projects above the mass of plaster of Paris. The flask is now swung to the closed position, Figures 1 and 2, and the edges 24 of the cups 20 and 21 contact to limit the closing movement of the arms 10 and 11. An impression is now made in the plaster of Paris mass of the other cup so that after the plaster of Paris has hardened and the flask is reopened, a complete mold of the invested work is formed.

In order to firmly yet resiliently secure the cups 20 and 21 in the closed position, I provide a strong rubber band B, which may be looped one or more times about the free ends of the arms 10 and 11 and criss-crossed one or more times over the closed cups, as shown in Figure 1. Finally, the last loop of the rubber band engages the hook 19 and is held in place thereby. The rubber band B may also engage the arcuate notches 17 of the arm 11, which tend to further position the rubber band so that it will not slip or loosen. This arrangement affords a constant, firm and yet resilient force holding the flask sections or cups together, and there is no liability of exerting too great a force on the work W, as sometimes happens when positive fastening means, such as screw-threaded turn buckles, bolts or the like are used for detachably securing companion flask sections together. Also, the rubber band arrangement is much simpler and more compact, enabling the device to be free from moving parts and screw-threaded fastener elements.

As shown in Figures 1 and 2, the work W to be invested may be in the form of a partial upper or lower bar which is generally arcuate in shape and having two sides each of which may carry one or more teeth. The use of my hinged flask makes it possible to invest one side only of the partial bar, while the other side projects beyond the cups 20 and 21 and the mass of molding material. Since the opposite ends of the cups 20 and 21 are entirely open, the work W may extend through either end of either cup, and the arcuate notches 25 in the bottoms of the cups form additional clearance space to permit the passage of the work or bar close to the side of the adjacent arm 10 or 11, as shown. The hinged flask of course is adapted for use in investing various types of work in addition to the partial bar shown in Figures 1 and 2, and the illustration in the drawing is merely illustrative of the manner in which a relatively small and curved piece of work is accommodated by the flask.

Since the opposite ends of the cups 20 and 21 are entirely open, it is very easy to dislodge the plaster of Paris from them. In conventional flasks having a side or sides extending entirely about the margin of the flask, it is much more difficult to dislodge the molding material, since the marginal side of the flask interferes with the knife or other implement used to dislodge the molding material. Also, the open end construction of the cups 20 and 21, which permits the

work W to project beyond the flask during the investment greatly facilitates dislodging the work W from the molding material, without bending or otherwise damaging the work, as sometimes happens when it is entirely embedded in the molding material of a conventional flask.

It is to be understood that the form of the invention herewith shown and described is to be taken as a preferred example of the same, and that various changes in shape, size and arrangement of parts may be resorted to, without departing from the spirit of the invention or the scope of the subjoined claims.

Having thus described my invention, I claim:

15 1. A dental flask comprising a pair of companion channel members which are generally U-shaped in transverse cross section and have their opposite ends open, the channel members being shiftable toward and from each other, the channel members having sides which are brought into close opposed relation when the channel members are shifted together so that the channel members form an open ended substantially tubular mold, and means connected with the channel members for releasably holding them together with their sides in close opposed relation.

20 2. A dental flask comprising a pair of companion opposed channel members which are hingedly connected and shiftable toward and from each other, the opposite ends of the channel members being open, the channel members being generally U-shaped in transverse cross section and having opposed sides adapted to move into close opposed relation when the channel members are shifted together so that the channel members then form an open ended substantially tubular mold.

25 3. A dental flask comprising a pair of companion opposed channel members which are hingedly connected and shiftable toward and from each other, the opposite end of the channel members being open, the channel members being generally U-shaped in transverse cross section and having opposed sides adapted to move into close opposed relation when the channel members are shifted together so that the channel members then form an open ended substantially tubular mold, and resilient means connected with the companion channel members for releasably holding them together with their sides in close relation.

30 4. A dental flask comprising a pair of hingedly connected arms which are swingable from extended to laterally opposed positions, and companion opposed channel members secured to corresponding sides of the arms and extending transversely of the arms, the opposite ends of the channel members being open so that work invested in either channel member may extend beyond either end of the same, the channel members having opposed sides adapted to substantially contact when the arms are swung to their laterally opposed positions, whereby the channel members form an open ended substantially tubular mold extending transversely of the arms.

35 5. A dental flask comprising a pair of hingedly connected arms which are swingable from extended to laterally opposed positions, companion opposed generally U-shaped channel members secured to the arms and extending transversely thereof and having their opposite ends open, the channel members having sides projecting beyond corresponding sides of the arms and adapted to contact when the arms are swung to their laterally opposed positions for forming a substantially

tubular open ended mold extending transversely of the arms, the channel members including bottom webs arranged next to and secured to the arms and having their ends projecting beyond the opposite longitudinal edges of the arms, there being notches formed in the ends of the bottom webs to provide clearance for work invested within the flask, and means connected with the arms for releasably holding them in their laterally opposed positions.

6. A hinged dental flask comprising a pair of arms hingedly connected near corresponding ends and adapted to swing to opened and closed positions, a hook element secured to one arm near its free end, the other arm being provided near its free end and in its longitudinal edges with notches arranged substantially opposite the hook element when the arms are in their closed substantially parallel spaced positions, the hook element and notches being engaged by a flexible

10

15

20

element for securing the arms in their closed positions, and opposed cups secured to the arms between their ends and including sides extending transversely of the arms and having substantially straight edges adapted to contact when the arms swing together to limit the closing of the arms, the ends of the cups being open, the cups having their ends arranged near the opposite longitudinal edges of the arms.
